[57] **CLAIM**

The ornamental design for a motor housing and rug
nozzle for a vacuum cleaner, as shown.

DESCRIPTION

FIG. 1 is a top plan view of a motor housing and rug
nozzle for a vacuum cleaner, showing my new design;
FIG. 2 is a front elevational view thereof;
FIG. 3 is a rear elevational view thereof;
FIG. 4 is a side elevational view thereof;
FIG. 5 is an elevational view of the opposite side
thereof.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 261,268
DATED : October 13, 1981
INVENTOR(S) : Sheldon Rutter

It is certified that error appears in the above-identified patent and that said Letters Patent is hereby corrected as shown below:

Front page, Column 2, under "CLAIM" [57] reads "The ornamental design for a motor housing and rug nozzle for a vacuum cleaner, as shown." Should read ---- The ornamental design for a vacuum cleaner as shown. -----

Signed and Sealed this

Sixteenth Day of March 1982

[SEAL]
